Y QUARTER BEND PLUMBING FITTING

Fred D. Buskirk, San Diego, Calif.

Application December 20, 1947, Serial No. 793,031

9 Claims. (Cl. 285—210)

1

My invention relates to a Y quarter bend plumbing fitting and the objects of my invention are:

First, to provide a fitting of this class which greatly reduces the overall elevation of plumbing installations from the lower portions of plumbing fixtures to the ditch level in which the drainage soil pipe is positioned;

Second, to provide a fitting of this class which greatly reduces the multiplicity of fittings required in the installation of a plumbing system;

Third, to provide a plumbing fitting of this class which provides for the disposition of clean outs above the surface of the ground for the cleaning of the base soil pipe;

Fourth, to provide a plumbing fitting of this class which greatly reduces the labor in the digging of soil pipe ditches due to the fact that the elevation of the plumbing assembly is reduced permitting the ditches to be shallower with respect to the upper surface of the ground;

Fifth, to provide a fitting of this class which greatly facilitates the insertion of a plumber's snake into the base soil pipe of a plumbing system; and

Sixth, to provide a Y quarter bend fitting of this class which is very simple and economical of construction, efficient in operation and which will not readily deteriorate or get out of order.

With these and other objects in view as will appear hereinafter, my invention consists of certain novel features of construction, combination and arrangement of portions and a certain modification as will be hereinafter described in detail and particularly set forth in the appended claims, reference being had to the accompanying drawing and to the characters of reference thereon forming a part of this application in which: Figure 1 is a side elevational view of my Y quarter bend plumbing fitting; Fig. 2 is a view showing a modified form thereof; Fig. 3 is an end elevational view of another modified form of my Y quarter bend plumbing fitting and Fig. 4 is a side elevational view of the fitting as shown in Fig. 3 of the drawing.

Similar characters of reference refer to similar parts and portions throughout the several views of the drawing.

The Y quarter bend fitting as shown in Fig. 1 of the drawing is provided with a 90 degree tubular portion 1 having Y portions 2 and 3 communicating therewith on a common plane with the plane of the curve of the 90 degree curved portion 1. These Y portions 2 and 3 are provided with hub portions 2a and 3a. The 90 degree

2

tubular portion designated 1a is provided with a male connection portion while the normally upper end thereof is provided with a hub 1b. The fitting disclosed in Fig. 2 of the drawing is similar to that shown in Fig. 1 of the drawing but is produced with a single Y portion 3 omitting the Y portion 2 as shown in Fig. 1 of the drawing which Y portion 3 may be used as a clean out plug support or may be used as a connector for branch lines. As shown in Fig. 3 of the drawing, I have provided a modified form of the Y quarter bend fitting as shown in Fig. 1 of the drawing, in which the 90 degree tubular portion 4 is provided with a pair of Y's 5 and 6 communicating therewith on a plane transverse to the plane of the 90 degree tubular portion 4. Thus, the fitting as shown in Figs. 3 and 4 of the drawing employs Y sections disposed substantially 90 degrees from those shown in Fig. 1 of the drawing. The 90 degree tubular portion 4 is provided with a male connection portion 4a at its lower end and a hub 4b at its upper end. Either of the Y portions 5 or 6 may be employed to retain a clean out plug in either the hub 5a or the hub 6a as desired, depending upon the particular installation.

The operation of my Y quarter bend plumbing fitting is substantially as follows:

The employment of my Y quarter bend plumbing fitting in the installation of a plumbing system substantially reduces the overall elevation of the system from the soil pipe or the base pipe to the fixtures at the floor of the building room. In this manner, the depth of the ditches may be greatly decreased which proportionately decreases the cost of labor for installing the plumbing. Clean out plugs inserted in either of the hubs 2a or 3a or in the hubs 5a or 6a shown in Fig. 3 of the drawing, permits these clean out plugs to stand above the surface of the ground which provides for the accessibility to the base soil pipe without inconvenience. It is obvious that the combination fitting normally employed in a conventional plumbing system entails the use of numerous other fittings which are not needed when using my Y quarter bend fitting. In addition, the installation of plumbing rising above the first floor is greatly facilitated due to the convenient Y structure of my Y quarter bend plumbing fitting. A plumber's snake inserted through a clean out in any of the Y portions of the Y quarter bend fittings as shown in Fig. 1 or 3 of the drawings, readily follows the long radius sweeping curvature of the 90 degree tubular members 1 or 4 and the resistance to travel

therein is greatly reduced by said long radius so that clean out operations are greatly facilitated and in addition the flow through the fitting is greatly improved.

Though I have shown and described a particular construction, combination and arrangement of portions and certain modifications, I do not wish to be limited to the particular construction, combination and arrangement but desire to include in the scope of my invention the construction, combination and arrangement and the modification substantially as set forth in the appended claims.

Having thus described my invention, what I claim as new and desire to secure by Letters Patent is:

1. In a Y quarter bend base plumbing fitting of the class described, the combination of a 90 degree curved tubular portion having a male fitting portion on the lower end and a female hub connection at the upper end and a Y portion angularly extending adjacent to said female hub portion disposed at substantially less than ninety degrees to said tubular portion and provided with a female hub portion at the end thereof, said Y-portion open upwardly near said female hub connection of said curved tubular portion.

2. In a Y quarter bend base plumbing fitting of the class described, the combination of a curved, 90 degree tubular bend having a male connection portion at the lower end and a female hub portion at the upper end and also provided with a pair of diverging Y portions disposed at substantially less than ninety degrees to said tubular portion and integral therewith and communicating with the interior thereof, said diverging Y-portion having female hub portions open upwardly near said upper female hub portion.

3. In a Y quarter bend base plumbing fitting of the class described, the combination of a curved, 90 degree tubular bend having a male connection portion at the lower end and a female hub portion at the upper end and also provided with a pair of diverging Y portions disposed at substantially less than ninety degrees to said tubular portion and integral therewith and communicating with the interior thereof, said Y portions having hub portions integral therewith adjacent the hub portion of said curved 90 degree tubular bend open upwardly.

4. In a Y quarter bend base plumbing fitting of the class described, the combination of a curved, 90 degree tubular bend having a male connection portion at the lower end and a female hub portion at the upper end and also provided with a pair of diverging Y portions disposed at substantially less than ninety degrees to said tubular portion and integral therewith and communicating with the interior thereof, said Y portions having hub portions integral therewith adjacent the hub portion of said curved 90 degree tubular bend, said Y portions disposed on a plane parallel with the plane of the curve of said 90 degree tubular bend and open upwardly.

5. In a Y quarter bend base plumbing fitting of the class described, the combination of a curved, 90 degree tubular bend having a male connection portion at the lower end and a female hub portion at the upper end and also provided with a pair of diverging Y portions disposed at substantially less than ninety degrees to said tubular portion and integral therewith and communicating with the interior thereof, said Y portions hav-

ing hub portions integral therewith adjacent the hub portion of said curved 90 degree tubular bend, said Y portions disposed on a plane transversely to the plane of the curve of said tubular 90 degree bend and open upwardly.

6. In a Y quarter bend base plumbing fitting of the class described, the combination of a curved, 90 degree tubular bend having a male connection portion at the lower end and a female hub portion at the upper end and also provided with a pair of diverging Y portions disposed at substantially less than ninety degrees to said tubular portion and integral therewith and communicating with the interior thereof, said Y portions having hub portions integral therewith adjacent the hub portion of said curved 90 degree tubular bend, said Y portions disposed on a plane parallel with the plane of the curve of said 90 degree tubular bend, said Y portions disposed at substantially 45 degrees to the axis of said tubular 90 degree bend and open upwardly.

7. In a Y quarter bend base plumbing fitting of the class described, the combination of a curved, 90 degree tubular bend having a male connection portion at the lower end and a female hub portion at the upper end and also provided with a pair of diverging Y portions disposed at substantially less than ninety degrees to said tubular portion and integral therewith and communicating with the interior thereof, said Y portions having hub portions integral therewith adjacent the hub portion of said curved 90 degree tubular bend, said Y portions disposed on a plane transversely to the plane of the curve of said tubular 90 degree bend, said Y portions disposed at substantially 45 degrees from the plane of the curve of said tubular 90 degree bend and open upwardly.

8. In a Y fitting, a hollow tubular portion having a male fitting portion on one end and a hub portion on the opposite end and provided with a curved portion intermediate this male portion and said hub portion, maintaining the same at substantially ninety degrees to each other axially, said hollow tubular portion having an integral Y portion angularly extending adjacent to said hub portion, disposed at substantially less than ninety degrees to said tubular portion.

9. In a Y fitting, a hollow tubular portion having a male fitting portion on one end and a hub portion on the opposite end and provided with a curved portion intermediate said male portion and said hub portion, maintaining the same at substantially ninety degrees to each other axially, said hollow tubular portion having an integral Y portion angularly extending adjacent to said hub portion, disposed at substantially less than ninety degrees to said tubular portion, said Y portion provided with a hub portion adjacent said first mentioned hub portion.
